US00D460348S

(12) **United States Design Patent** (10) Patent No.: **US D460,348 S**
 Crawford et al. (45) Date of Patent: ** Jul. 16, 2002

(54) **CONTAINER WITH PUMP**

- (75) Inventors: **John C. Crawford**, Mahopac, NY (US); **Ronald Wadsworth**, Cambria; **Francois Danielo**, Hacienda Heights, both of CA (US)
- (73) Assignee: **Colgate Palmolive Company**, New York, NY (US)
- (**) Term: **14 Years**
- (21) Appl. No.: **29/138,564**
- (22) Filed: **Mar. 15, 2001**
- (51) LOC (7) Cl. **09-01**
- (52) U.S. Cl. **D9/300; D9/549**
- (58) Field of Search D9/300, 500, 504, D9/529, 549, 572-574; 215/371; 222/153.13, 321.1-321.9, 382, 383.1, 384, 531, 533-534, 556

(57) **CLAIM**

The ornamental design for a container with pump, as shown and described.

DESCRIPTION

FIG. 1 is a perspective view of the container with pump of our design.

FIG. 2 is a left side elevation view thereof.

FIG. 3 is a right side elevation view thereof.

FIG. 4 is a front elevation view thereof, the rear elevation view being a mirror image thereof.

FIG. 5 is a top plan view thereof.

FIG. 6 is a bottom plan view thereof; and,

FIG. 7 is a left side elevation view of an alternate embodiment, the other views being the same.
